UNITED STATES PATENT OFFICE.

HJALMAR G. CARLSON, OF WORCESTER, MASSACHUSETTS, ASSIGNEE TO ROCKWOOD SPRINKLER COMPANY OF MASSACHUSETTS, OF WORCESTER, MASSACHUSETTS, A CORPORATION OF MASSACHUSETTS.

FLIER CROWN.

Application filed December 29, 1923. Serial No. 683,330.

In my application for patent, Serial No. 665,210, filed Sept. 27, 1923, I have described a flier for spinning frames made of pressed metal and I have shown various parts thereof.

The principal object of this invention is to provide a crown of the flier shown in that application, or a crown of similar character, adapted to be assembled with the bearing stem, hollow thread guide and balance rod all made separately.

This invention involves a crown in one piece that can be made from pressed metal by a series of die pressing operations.

Reference is to be had to the accompanying drawings, in which

Figs. 1 and 2 are side and edge views of the original blank cut out from the sheet stock to be used for the manufacture of a crown in accordance with this process;

Figs. 3 and 4 are similar views showing the result of the first step of the operation;

Fig. 5 is a sectional view on the line 5—5 of Fig. 3;

Figs. 6 and 7 are side and edge views showing the next step in the process;

Fig. 8 is a sectional view on the line 8—8 of Fig. 6;

Figs. 9 and 10 are similar views showing the next step;

Fig. 11 is a transverse sectional view on the line 11—11 of Fig. 9;

Figs. 12 and 13 are views similar to Figs. 9 and 10 showing the alteration of the blank therein by bending it to throw the hubs for the balance rod and thread guide out of alignment with the rest of the blank to prepare it for the next operation;

Figs. 14 and 15 are similar views showing the final result of the process; and

Fig. 16 is a sectional view on the line 16—16 of Fig. 15 showing the cross-section.

For the purpose of making a crown as shown in Figs. 14, 15 and 16 I take a sheet of metal and cut it out by cutting dies into the form A shown in Fig. 1. This has the original thickness of the metal stock as indicated in Fig. 2.

The next step of the process is indicated by the blank B shown in Figs. 3, 4 and 5. This is formed from the blank A by compressing it to thin the edges of the stock and to form two convex surfaces 20 on the arms substantially from end to end thereof

and provide it with three bosses 21, 22 and 23. The two end bosses 21 and 23 are substantially round while the central boss 22 is somewhat oblong in shape. These are formed by providing three circular depressions 24, 25 and 26 in the back and extending part way through the bosses. These bosses have their outer faces at a slightly greater distance from the rear of the blank than was the original thickness of the blank A because of the depressions made behind them. One of these depressions is provided with an extension 27 which constitutes a thread guide in the finished article, as will appear.

This blank is then put into another set of dies, the thickness of its edges diminished slightly and three perforations 28, 29 and 30 are formed by extending the depressions 24, 25 and 26. These perforations are smaller than the depressions and of course extend all the way through the bosses. At the same time the bosses are somewhat finished off on their convex surfaces in the dies and their extreme convex ends can be ground off flat, as indicated in Fig. 7, if desired. It will be noticed that this blank C has a convex surface 31 on one side and that it has a flat edged flange 32 all the way around it and of substantially the same thickness throughout.

The blank C shown in Figs. 6 and 7 is then placed in a set of cutting and shaping dies. In these dies the flat flange 32 is cut off, leaving the outline of the blank D, shown in Figs. 9, 10 and 11. It will be seen by reference to Fig. 11 that the thread guide groove 27 is practically unchanged all this time. In fact, the surface in which this is located has remained flat and level throughout the operations up to the present time. In these dies the three bosses previously referred to are shaped up further and finished so as to have cylindrical surfaces. The perforations through these bosses are also enlarged to their final size so as to fit accurately the three elements which are to be placed in them and brazed or otherwise secured to them to form the finished article. The convex end edges of the bosses can be ground or otherwise finished off after this dieing operation to the shape shown in Fig. 10.

Now the blank is placed in a bending die

and the two end bosses are bent out of the plane of the back as indicated in the blank E shown in Figs. 12 and 13. No other change is made at this time.

5 The final operation is to bend the two arms of this blank to form the finished article F shown in the last three figures. This bending takes place at the points 35 just at the opposite sides of the middle 10 bosses 22. No further bending of the two end bosses 21 and 23 has to be done at this time. This finished article is of the well known shape of a crown for a flier. It contains the three perforations above specified 15 which are shaped by the dies and sized inside to exactly the proper sizes to receive in them the bearing stem, the hollow guide and the balance rod. These three elements are not shown herein as they constitute no 20 part of the present process but they are shown in my above identified application. They are inserted in their respective perforations which they fit accurately and are brazed thereto or otherwise secured and when this is done the flier itself is completed. 25

It will be noticed that up to the formation of the blank D shown in Figs. 9 and 10, the three bosses 21, 22 and 23 are arranged with their rear ends in the same plane. In other 30 words there is no boss on the rear of the article. Their opposite ends are in parallel planes. Also, the perforations through them are made on parallel axes. However, in the next blank E the two bosses 21 and 23 35 are bent backwardly and outwardly away from this plane so that they come into angular relation with each other. Then in

forming the final article F from the blank E the arms of the article are bent in the opposite direction at a point near the boss 40 22 so as to bring the two bosses 21 and 23 back into parallel relationship. They are not brought back into the same plane as the boss 23, but are projected further from the base of the article than the boss 21. 45 The axes of the perforations are parallel with each other and the end surfaces of the three bosses are also in parallel planes. This provides the two slanting arms and the three bosses perforated on parallel axes so that 50 the three elements that are inserted and fixed in them will be parallel with each other. The two bosses 21 and 23 are not necessarily at exactly the same distance from the central 55 boss.

Although I have illustrated and described only a single form of the invention I am aware of the fact that modifications can be made therein by any person skilled in the art without departing from the scope of the invention as expressed in the claims. Therefore I do not wish to be limited to all the details of construction and procedure herein shown and described but what I do claim is:—

As an article of manufacture, a flier crown piece formed of sheet metal and having two integral end bosses, and an integral boss at the center, said end and central bosses being perforated all the way through for the purpose described.

In testimony whereof I have hereunto affixed my signature.

HJALMAR G. CARLSON.
